UNITED STATES PATENT OFFICE.

JOHN W. McKEEHAN, OF BERKELEY, CALIFORNIA.

SPRING-CLOTHESPIN.

1,330,205.

Specification of Letters Patent. Patented Feb. 10, 1920.

Application filed March 3, 1918. Serial No. 81,858.

To all whom it may concern:

Be it known that I, JOHN W. McKEEHAN, a citizen of the United States, and a resident of the city of Berkeley, county of Alameda, 5 State of California, have invented a new and useful Improvement in Spring-Clothespins; and I hereby declare the following to be a full, clear, concise, and exact description of the same.

10 This invention relates more particularly to push clothes-pins, in which the jaws of pin are connected by a resilient element arranged and combined in such a manner that the clothes-pin can be pushed onto the line, 15 avoiding the necessity for pinching it open for that purpose.

In this specification and the annexed drawing, I illustrate the invention in the form that I consider the best, but it is to 20 be understood that I do not limit myself to such form, because the said invention may be embodied in other forms, and it is also to be understood that in and by the claims following the description herein, I desire 25 to cover the invention in whatever form it may be embodied.

Referring to the accompanying one sheet of drawings:

Figure 1 is a perspective view of a clothes- 30 pin constructed in accordance with my invention.

Fig. 2 is a modified form of the same.

Fig. 3 illustrates one manner of suspending 35 an article to the line by attaching one end of the pin to the line and the other end to the article.

Fig. 4 is a similar view illustrating a modified manner of using the pin, in which two of the pins are pushed over the line having 40 the article folded thereover, and a third pin in the center illustrating the use of the clamping end of the pin for holding the article in position on the line by direct pressure.

In structural detail the clothes-pins illustrated in the drawings include: two jaws 45 1-1 alike in construction having transverse grooves therein and held in juxtaposition with the grooves in registry, by a clamping spring. The spring clamp joining the opposed jaws of the clothes-pin consists of a length of wire extending through the trans- 50 verse opening 2 between the jaws of the clothes-pin, thence at right angles at the point 3 on opposite sides of the jaws 1, from 55 which point the wire is bent preferably in a true circle to form the scroll 4, the diam-

eter of the scroll being approximately equal to the combined thickness of the jaws 1-1. The extensions 5-5 extend down the edges of the clothes-pin at a tangent to the circle 60 of the scroll 4 to the bend 6, at which point the wire extends forward in the extensions 7-7 on opposite sides of the clothespin to the bend 8, at which point they are bent at a right angle to the extensions 7, the terminals 9-9 within the grooves provided therefor across the jaws. The extensions 9-9 lie parallel on opposite sides of the jaws 1-1 confined therebetween. The jaws 1-1 are held in lateral alinement in juxtaposition against the lateral off-setting by the scrolls 4-4 and the extensions 7-7 on the opposite edges of the clothes-pin.

The jaws 1-1 are provided with registering grooves which form the openings 2 and 75 11. The opening 3 is preferably intermediate the center of the length of the jaws and one of their ends and closer to the center of the length of the pin; the extensions 9-9 of the clamp engaging the jaws 80 beyond the center of the length thereof. The lower ends 13-13 of the opposing jaws taper to the shoulders 14-14 forming the lower extremity of the opening 10 tapering upward to the point of conjunction from 85 which point the inner faces of the jaws 1-1 lie in contact up to the opening 2. The openings 2 and 11 are joined by the slot 6 which allows a certain freedom to the cross bar of the clamp in the slot 2 allowing for variations in the length of the clamp between the cross bar 2 and the ends 9-9: the inner faces of the opposing jaws lie in contact at the point 17 between the openings 11 and 12. From the opening 12 the jaws are tapered outwardly to the end 18-18.

The long taper of the opposed jaws from 13 to 14 permit this end of the pin to be pushed over the line on which the article is to be hung without the necessity of pinching 100 the jaws at the ends 18-18 to open the pin. This is a substantial advantage as the user, particularly if it be a woman, has more power to push the pin over the line than to spread it by pinching the ends, curing one 105 of the particular disadvantages of the ordinary type of clamp pin. The jaws automatically spread to accommodate any thickness of material to be confined therebetween. In opening the pin at the ends 13-13 110 against the tension of the spring member, the jaws fulcrum at the point 17. The illus-

tration in Fig. 3 discloses a very convenient manner of using the pin, consisting in attaching it to the upper edge of the article X, which may be very conveniently done 5 while the article is still in the basket or in convenient reach, and pushing the opposite end 18 upward until the line engages the transverse opening 12 or 11. The opening 12 is intended to engage the ordinary woven 10 clothes-line, or rope, and the opening 11 which is smaller is adapted to engage wire or smaller metal clothes-lines. The article X is thus suspended without touching the line X¹ that is apt to be soiled or subject to 15 rust and other conditions liable to soil the article X.

In Fig. 4 a modified manner of using the clothes-pin is illustrated, in which the article X² is folded over the line X³ and held in 20 position by the jaws of the clothes-pins X⁴ and X⁵ inserted thereover from the ends 13—13 as is common to all the conventional forms of wooden clothes-pins.

The center pin X⁶ is shown in the reverse 25 position with the end 18 clamped over the article and the line, this end of the pin can be pushed over the line, or the opposing jaws may be sprung open by pressure applied at the ends 13—13, the jaws opening 30 from the fulcrum at 14. The pin thus applied is very effective but not so easily operated.

The modified form of clothes-pin shown 35 in Fig. 2 is similar in every respect to that illustrated in Fig. 1, except that the upper end is cut off above the point 17, leaving the blunt ends 19—19, by reason of which the pin can be very comfortably pushed over the edge of the fabric when used as 40 illustrated in Fig. 3 or as at X⁴, X⁵ in Fig. 4. In this modified form the line X¹ engages the hole 20 between the opposed jaws 21—21.

A double-ended pin made according to 45 this invention is adapted to be used as a push pin, or reversed and used as a clamp pin, or either end may be used as a push pin or either end as a clamp pin. By its use the article to be dried can be hung without 50 touching the clothes-line, avoiding the danger of soiling from this source.

The spring member may be made in a variety of shapes, that preferred by me being illustrated, in which the extensions 7

cross over at substantially a right angle to 55 the length of the pin, preventing the clothes or line from being forced between the jaws beyond the bars 7.

Having thus described this invention, what I claim and desire to secure by Letters 60 Patent is:

1. A double ended clothes-pin including two parallel jaws having both ends tapering inwardly toward the contiguous jaw to form acutely tapered entrances between said 65 jaws at both ends and also to form means for operating the jaws at both ends thereof, and transverse grooves to form openings behind said entrances, and a single resilient metallic joining member having a relatively 70 straight or unbent portion passing transversely between said jaws and having oppositely disposed ends clamping said jaws therebetween.

2. A double ended clothes pin including 75 a pair of jaws provided with means at their opposite ends for manually operating the pin, a single resilient joining member engaging said jaws, fulcrums on said jaws at opposite sides of said joining member, one 80 of said fulcrums being farther away from the center of the pin than the other and being so disposed with respect to the joining member that the resilient tension between the jaws is greater at one end of the pin 85 than at the other.

3. A double ended clothes pin comprising two co-acting rigid members adapted to normally contact with each other adjacent their opposite ends, said contacting portions 90 forming fulcrums adjacent the opposite ends of the pin, a single resilient member engaging said members and disposed between said fulcrums and diverging portions on both ends of said members beyond the 95 fulcrums whereby inward pressure on either pair of diverging portions will cause the rigid members to rock on the adjacent fulcrum and cause the contacting portions at the other end of the pin to separate. 100

In testimony whereof, I have hereunto set my hand at San Francisco, California, this 25th day of February 1916.

JOHN W. McKEEHAN.

In presence of—
RODNEY M. SMITH,
BALDWIN VALE.
